United States Patent

Des. 242,456
Patented Nov. 23, 1976

242,456

TOILET FOR CHILDREN

Lucinda Willis, 4108 Hillcrest Drive,
Los Angeles, Calif. 90008

Continuation-in-part of design application Ser. No.
549,538, Feb. 13, 1975. This application Aug. 11, 1975,
Ser. No. 603,285

Term of patent 14 years

Int. Cl. D23—02

U.S. Cl. D23—53

Fig. 1

Fig. 3

Fig. 2

Fig. 4

FIG. 1 is a side view of a toilet for children showing my new design;

FIG. 2 is a front view thereof;

FIG. 3 is a top plan view thereof; and

FIG. 4 is a rear view thereof.

This is a continuation-in-part of design application Ser. No. 549,538, filed Feb. 13, 1975, now abandoned.

I claim:

The ornamental design for a toilet for children, substantially as shown.
